UNITED STATES PATENT OFFICE.

FREDERICK G. KEYES, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

ELECTRIC LAMP.

1,292,482.

Specification of Letters Patent.

Patented Jan. 28, 1919.

Application filed February 11, 1914. Serial No. 818,005.

To all whom it may concern:

Be it known that I, FREDERICK G. KEYES, a citizen of the United States, and resident of East Orange, county of Essex, State of New Jersey, have invented certain new and useful Improvements in Electric Lamps, of which the following is a specification.

It has been found in practice that the presence of a trace of moisture in metal filament lamps increases very materially the rate at which the discharge of particles from the filament and the consequent blackening or darkening of the light transmitting envelop takes place. The water vapor is diffused over the hot filament and is there practically completely dissociated, the oxygen uniting with the filament material. In the case of tungsten, the oxid is liquid at the temperature at which the filaments are operated. Under these conditions the oxid is suddenly transformed into vapor and deposits upon the cooler glass surfaces. Oxygen in its free state will, of course, unite directly with the tungsten or other metallic material, producing the same result. Consequently it is advisable to introduce into the lamp a substance which will effectively absorb minute traces of water vapor and oxygen. As a suitable material for this purpose, I propose calcium or other alkaline earth metals, or alkali metals, usually in the form of turnings or powder. The heat engaged while the lamp is in operation increases the chemical activity of the alkaline earth metal and increases the rate at which water vapor and oxygen will be absorbed.

My invention is illustrated in the accompanying drawings in which Figure 1 is a vertical section through the major portion 40 of a tungsten lamp, the lower part of the globe being shown without section lines, and Fig. 2 is a plan of a tungsten filament well suited for use in connection with lamps of this character; and Fig. 3 is a detail view 45 of a modification.

In the drawings 1 is the outer globe of a tungsten lamp and 2 a tubular extension thereof having a reentrant portion, 3, within which the sealing of the lamp is accomplished.

The tungsten filament is shown at 4 and is provided with terminal pieces, 5, 5, which are connected in any suitable manner (herein shown as a screw thread connection) 55 with the lower ends of leads, 6, 6. The fila-

ment is shown as a spiral, and at several points therein the spiral is spread out, as shown at 7, 7, so as to prevent the contacting of adjacent coils of the spiral at points where the filament sags naturally by reason of the weight of the filament or for any other reason. Anchor wires, 8, 8, are shown tipped with tungsten wire, 9, 9. This wire is bent around the spread out portions of the filament whereby adequate support is provided. The leads 6, 6 and the anchor wires 8, 8 are shown as passing up through a diaphragm, 10, of aluminum or some other suitable metal, the said parts where they pass through the diaphragm being surrounded by sleeves, 11, 11, of quartz and being covered at the top of the diaphragm with masses, 12, 12, of paste or cement formed of some vitreous adhesive material whereby, in the case of the lead 6, 6 the leads 70 themselves are held from twisting as will be readily understood. At the top of the wires 6, 6 sockets, 13, 13, are sealed on. These may be of any convenient depth, and they are adapted to receive the lower ends of copper 80 leads, 14, 14, which pass through sleeves 16, 16, of platinum; and the parts are all secured together by iron caps, 17, 17, which are welded to the platinum tubes and to the 85 tops of the leads 14, 14.

In the present instance the metallic diaphragm 10 is supported in a manner presently to be described. The object of the diaphragm is to prevent the entrance of unnecessary or undue heat into the tubular extension 2 where the sealing of the lamp takes place.

To the bottom of the reentrant portion is secured or made integral a solid piece of glass, 18, to the lower end of which is secured a glass tube, 19, which is itself secured at the bottom to another solid glass piece, 20, having a shoulder, 21 and a lower portion which passes through the metal diaphragm 10. After being passed through 95 the diaphragm this solid lower end is formed into a second shoulder, 22, lying underneath the diaphragm 10, so that the latter is held firmly by the glass portion 20 and its shoulders 21 and 22.

Near the top of the tubular portion 19 are formed holes or openings, 23, and one of the first operations is to invert the tube and place inside it a small piece, 24, of glass wool. Calcium or some alkali or alkaline 110

- earth metal in the form of powder or turnings is now introduced at the bottom of the tube, but is prevented from passing out through the openings 23 by the glass wool 5
- 5 24. The mouth of the tube 19 is then closed by another piece, 25, of glass wool and the alkali or alkaline earth is held within the tube. The lower solid part, 20, is thereupon secured to the tube end in 10 order to complete the structure. Thereafter the lead connections are made by means of the sockets and set screws already described and the seal mountings are disposed in compact form. As there is no 15 strain upon the diaphragm 10 pressing upon the leads 6, 6, the ends of the copper lead wire coming from the seals may conveniently be coiled, as shown at 26, 26.
- The alkaline earth metal or alkali, as the 20 case may be, serves to absorb the excess of water vapor which may find its way into the extension 2 and also to take up the oxygen which might combine with the metal of the filament and cause a deposition of 25 particles therefrom upon the inner wall of the globe 1.
- It will be understood that the particular 30 location given to the tube 19, within the extension 2, is not an essential feature of the invention. The parts numbered in the other figures of the drawing as 18, 19 and 20 are here shown as of solid glass, and a tubular portion 30 is suspended below the disk 10 where its contents, being exposed 35 to higher temperature will be increasingly active.
- I claim as my invention:
1. In a tungsten lamp, a globe containing a filament of tungsten, lead wires for the 40 said filament, a tubular extension of said globe within a reentrant portion of which the lamp seals are mounted, a dependent piece of glass, centrally tubular, integral with the bottom of the said reentrant portion and absorbent material in finely divided form within the said tubular portion, the said absorbent material being remote from the lamp filament.
  2. In a tungsten lamp, a diaphragm separating two portions of the lamp globe, a piece of glass, centrally tubular, depending from one end of the inclosing globe and supporting the said diaphragm by means of shoulders above and below the same, the shoulders being formed on a solid portion 55 of the glass piece, and the diaphragm being remote from the lamp filament.
  3. In a tungsten lamp, a suitable globe, a filament of tungsten within said globe, a tubular extension of the globe and a diaphragm substantially closing off the tubular extension from the globe, in combination with lead wires for the filaments and a suitable support for the diaphragm independent of the lead wires.
  4. In an incandescent electric lamp, a diaphragm, terminal lead wires passing through the same and a support for the diaphragm independent of the lead wires.
  5. In an incandescent electric lamp, a diaphragm, terminal lead wires passing through the same, a support for the diaphragm independent of the lead wires, the lead wires which pass through the diaphragm being connected to special flexible copper leads, 75 and seals for the said copper leads.
  6. In an incandescent electric lamp where injurious gases are developed during operation, a globe containing a filament adapted to be brought to incandescence, a tubular 80 extension of said globe, a diaphragm substantially closing off the extension from the globe so as to prevent undue heat within the extension, in combination with a hollow insulating container, an absorbent material 85 within the same, supported below the said diaphragm, but remote from the lamp filament.

Signed at New York in the county of New York and State of New York this 10th 90 day of February, A. D. 1914.

FREDERICK G. KEYES.
